ABSTRACT OF THE DISCLOSURE

Hydroxy alkyl amino salts of nopinic acid as new compounds useful in pharmaceutical compositions for alleviating ulcer conditions.

This invention relates to new pharmaceutical compositions and particularly to compositions suitable for the prevention and control of ulcers and/or of the pain due to ulcers, particularly ulcers of the digestive tract, such as the ulcers of the gastro-duodenal tract, as well as the skin ulcers.

It has now been found that β -pinene and derivatives thereof have surprisingly very interesting pharmacological properties in the field of the prevention and control of ulcers and/or of the pain due to ulcers.

The pharmaceutical compositions according to this invention contain, as active ingredient, at least one compound of the following general formula:

(I)

in which Z represents a $>\text{C}=\text{CH}_2$ group or a group of the formula

in which X represents hydrogen, a cation of an alkaline metal or ammonium, a lower alkyl radical or a group of the formula

in which n=1 to 3 inclusive, whereas R and R', which may be similar or different, represent a lower alkyl radical, or a group of the formula

in which n, R and R' have the above indicated meaning.

Among the compounds of the general Formula I, some compounds are known and others are now.

Thus, β -pinene or nopinene is a known compound of the formula:

(II)

which can be easily isolated from turpentine oil. B.P.: 161–163°C; $[\alpha]_D = -21\text{--}22^\circ$.

2

Moreover, the nopinic acid and the alkaline metal salts thereof of the formula

(III)

are also known.

10 However, the pharmaceutical compositions may also contain, as active ingredient, compounds of the general formula I which are new compounds. These new compounds may be represented by the following general formulae:

(IV)

in which X' represents a lower alkyl radical or a group of the formula:

in which n=1 to 3 inclusive, whereas R and R', which may be similar or different, represent hydrogen or a lower alkyl radical; and

(V)

in which n=1 to 3 inclusive, whereas R and R', which may be similar or different, represent hydrogen or a lower alkyl radical.

Among the new compounds of Formula IV, the following may be cited as examples:

- 45 ammonium nopinate
methyl nopinate ($\text{X}' = -\text{CH}_3$)
ethyl nopinate ($\text{X}' = -\text{C}_2\text{H}_5$)
n-propyl nopinate ($\text{X}' = -\text{n-C}_3\text{H}_7$)
isopropyl nopinate ($\text{X}' = -\text{iso-C}_3\text{H}_7$)
aminoethyl nopinate ($\text{X}' = -(\text{CH}_2)_2-\text{NH}_2$)
50 dimethylaminoethyl nopinate ($\text{X}' = -(\text{CH}_2)_2-\text{N}(\text{CH}_3)_2$)
diethylaminoethyl nopinate ($\text{X}' = -(\text{CH}_2)_2-\text{N}(\text{C}_2\text{H}_5)_2$)
monomethylaminoethyl nopinate ($\text{X}' = -(\text{CH}_2)_2-\text{N}(\text{CH}_3)-\text{C}_2\text{H}_5$)
60 diisopropylaminoethyl nopinate ($\text{X}' = -(\text{CH}_2)_2-\text{N}(\text{iso-C}_3\text{H}_7)_2$)
di-n-butylaminoethyl nopinate ($\text{X}' = -(\text{CH}_2)_2-\text{N}(\text{n-C}_4\text{H}_9)_2$)
70 dimethylaminopropyl nopinate ($\text{X}' = -(\text{CH}_2)_3-\text{N}(\text{CH}_3)_2$)

Among the new compounds of Formula (V), the following may be cited:

aminoethanol salt of nopic acid ($R=R'=H$; $n=2$)
dimethylaminoethanol salt of nopic acid ($R=R'=CH_3$;
 $n=2$)

diethylaminoethanol salt of nopic acid ($R=R'=C_2H_5$;
 $n=2$)

monomethylaminoethanol salt of nopic acid
($R=H$; $R'=-CH_3$; $n=2$)

disopropylaminoethanol salt of nopic acid
($R=R'=iso-C_3H_7$; $n=2$)

di-n-butylaminoethanol salt of nopic acid
($R=R'=-n-C_4H_9$; $n=2$)

dimethylaminopropanol salt of nopic acid
($R=R'=CH_3$, $n=3$).

This invention includes as new compounds the esters and salts of nopic acid of the Formula IV and V, as well as the acid addition salts, such as the hydrochlorides of the compounds of the Formula IV.

The pharmaceutical compositions according to the present invention are generally intended for peroral, topical or parenteral administration. Therapeutical compositions to be administered perorally may, for example, be in the form of tablets, dragees, capsules, in which at least one compound selected among the compounds of the general Formula I is mixed with a solid pharmaceutically acceptable vehicle or excipient.

The therapeutical compositions may also be used in the form of ointments or creams for the treatment of skin ulcers, said ointments or creams containing at least one compound selected among the compounds of the Formula I mixed to an usual pharmaceutical cream or ointment base.

The therapeutical compositions can also be used in the form of liquid preparations for oral administration, especially syrups, elixirs, aqueous dispersions or solutions.

The therapeutic compositions according to the present invention can also be used in the form of solution to be administered parenterally. Solutions or suspensions for injection purpose can be prepared by using, for example, distilled water or sterile a pyrogenic water, in which at least one compound of the aforementioned Formula I is dissolved or suspended, if desired in the presence of a dissolving or stabilizing agent, such as propylene glycol.

Finally, it is possible for a compound selected among the compounds of general Formula I to be administered rectally, by incorporating it in a composition for suppositories, for example in cocoa butter.

β -pinene and the compounds of the general Formulae III, IV and II can be administered in varying doses, depending on the particular compound being used, the condition of the patient and the method of administration.

Thus, the compounds in question can be administered in doses from 50 to 600 mg. per day, in the form of several doses taken throughout the day.

The invention relates also to processes for the preparation of the new compounds represented by the Formulae IV and V.

The alkyl esters as well as the aminoalkyl esters of nopic acid of the Formula IV may be prepared by the usual esterification methods, such as:

(1) Heating of nopic acid in the suitable esterification alcohol, possibly in the presence of a catalyst such as hydrochloric acid or p-toluene sulphonic acid, with or without azeotropic removal of the formed water;

(2) Transesterification

(3) Reaction of alkaline salt of nopic acid with an appropriate alkyl halide or aminoalkyl halide.

The aminoalkanol salts of nopic acid of the Formula V may be prepared by dissolving nopic acid in an anhydrous organic solvent, by neutralizing the solution with a stoichiometric quantity of the suitable aminoalcohol dissolved in the same solvent and by concentrating to dryness.

Examples of methods for the preparation of the compounds used in the pharmaceutical compositions according to this invention, as well as several examples of pharmaceutical compositions are given below for illustrative purposes.

EXAMPLE 1

Preparation of nopic acid

This acid may be prepared by oxidation of β -pinene by means of potassium permanganate or another oxidizing agent, the reaction being carried out in an aqueous alkaline medium, by the following procedure:

392 grams of caustic potash and 2,212 grams of potassium permanganate are dissolved in 31 liters of deionized water. While stirring vigorously, 952 grams (7 moles) of β -pinene are added. The reaction mixture is maintained during 3 to 5 hours at a temperature of 25–30° C., by adding ice to said reaction mixture. The reaction is complete when all the potassium permanganate has reacted. The obtained suspension containing MnO_2 is filtered and the precipitate is washed with deionized water. The filtrate is concentrated under vacuum to a volume of 10 liters. 420 grams of dry sodium sulphate are then added. After standing during one night in a refrigerator, the obtained sodium nopicate is filtered and washed with ice water.

The crude sodium nopicate is dissolved in 5–6 times its weight of boiling water. The obtained solution is filtered and cooled during one night in a refrigerator. The purified sodium nopicate is then filtered, washed with ice water and dried at low temperature.

The purified sodium nopicate is suspended into 5 times its weight of water and 7 times its weight of methylene chloride. Hydrochloric acid is added to the mixture until it is strongly acid and the sodium nopicate disappears. The organic phase contains the nopic acid. The aqueous solution is extracted three times with small fractions of methylene chloride and these fractions are combined with the organic phase. The combined organic fractions are washed with small fractions with deionized water and then dried by means of anhydrous sodium sulphate. The solution is filtered and concentrated to dryness. The residue is recrystallized from warm benzene. Yield: 25–30%; melting point: 126–127° C.; $[\alpha]_D^{20} = -16.4^\circ$ (methanol, 5%).

EXAMPLE 2

Preparation of alkaline metal and ammonium salts of nopic acid

These salts may be prepared by dissolving nopic acid in methanol or another solvent. The solution is neutralized by the stoichiometric quantity of a suitable base dissolved in methanol. The methanol is removed under vacuum.

For preparing ammonium nopicate, for example, 1.8 g. of pure nopic acid are dissolved into 20 ml. of methanol and the alcoholic solution is exactly neutralized with a titrated solution of gaseous ammonia in methanol. The methanol is removed under vacuum. The obtained ammonium nopicate is soluble in water.

EXAMPLE 3

Preparation of methylnopicate

10 g. of sodium nopicate are refluxed during 18 hours with 20 g. of methyl iodide dissolved in 100 ml. of methanol. The mixture is then concentrated to dryness. 25 ml. of water are added to the residue and the aqueous solution is extracted several times with 20 ml. of methylene chloride. The combined extracts are dried on anhydrous sodium sulphate and the methylene chloride is evaporated. The methyl nopicate is distilled under reduced pressure. Yield: 76%. This product is a liquid which is not miscible with water, but may be dissolved in organic solvents.

5

EXAMPLE 4

Preparation of the dimethylaminoethyl ester of nopic acid and the hydrochloride thereof

7 g. of methyl nopicinate prepared as described in Example 3 are heated during 12 hours at 100° C. in the presence of 50 ml. of dimethylaminoethanol and 1 g. of sodium. The excess of dimethylaminoethanol is removed by concentration to dryness. The solid residue is suspended in 100 ml. of ether. 50 ml. of water are added, whereafter methanol is added in a sufficient quantity for dissolving again the precipitate. The organic (ether) phase is collected and the aqueous phase is extracted three times with 50 ml. of ether. The ether extracts are combined and washed 5 times with 25 ml. of water. The ether solutions are dried on anhydrous magnesium sulphate. After distillation of the ether, a solid residue of dimethylaminoethyl nopicinate is obtained.

For obtaining the hydrochloride of this base gaseous hydrochloric acid is bubbled into an ether solution of said base until saturation is reached. The hydrochloride precipitates: M.P. 226° C. This salt may be recrystallized from a mixture (1:3) of methanol and isopropanol. Fine white needles melting at 230–231° C. are obtained. This product is soluble in water and methanol, insoluble in ether, benzene and hexane.

EXAMPLE 5

Preparation of the aminoethyl ester of nopic acid and the hydrochloride thereof

This compound and the hydrochloride thereof is prepared as described in Example 4 from methyl nopicinate, aminoethanol and sodium.

The hydrochloride melts at 146° C.

EXAMPLE 6

Preparation of the monomethylaminoethyl ester of nopic acid and the hydrochloride thereof

These compounds are prepared by the process described in Example 4 from methyl nopicinate, monomethylaminoethanol and sodium.

The ester melts at 144–145° C. The hydrochloride melts at 141–143° C. after recrystallization from acetone.

EXAMPLE 7

Preparation of the diisopropylaminoethyl ester of nopic acid and the hydrochloride thereof

These compounds are prepared by the process described in Example 4 from methyl nopicinate, diisopropylaminoethanol and sodium. The hydrochloride melts at 179–180° C. after recrystallization from a mixture of benzene and acetone.

EXAMPLE 8

Preparation of the di-n-butylaminoethyl ester of nopic acid and the hydrochloride thereof

These compounds are prepared by the process described in Example 4 from methyl nopicinate, di-n-butylaminoethanol and sodium. The hydrochloride cannot be crystallized.

EXAMPLE 9

Preparation of the dimethylaminopropyl ester of nopic acid and the hydrochloride thereof

These compounds are prepared by the process described in Examples 4 from methyl nopicinate, dimethylaminopropanol and sodium. The hydrochloride melts at 90–91° C.

EXAMPLE 10

Preparation of the dimethylaminoethanol salt of nopic acid

18.4 g. of nopic acid are dissolved in 100 ml. of methylene chloride and 8.9 g. of dimethylaminoethanol

6

are added. The mixture is refluxed during 30 minutes and then concentrated to incipient crystallization. After crystallization during one night, the suspension is filtered and the crystals are washed with anhydrous ether. The obtained product melts at 62–63° C.; $[\alpha]_D^{20} = -17^\circ$ (methanol, 10%). The product is soluble in water methanol, ethanol, acetone, benzene and liquid chlorinated hydrocarbons and insoluble in ether, pentane and hexane.

EXAMPLE 11

Preparation of the aminoethyl salt of nopic acid

This compound is prepared as described in Example 10 from nopic acid and aminoethanol. After recrystallization from a mixture of ethanol and benzene, the compound melts at 155° C.

EXAMPLE 12

Preparation of the monomethylaminoethanol salt of nopic acid

This compound is prepared as described in Example 10 from nopic acid and monoethylaminoethanol. This compound melts at 99–100° C. after recrystallization from benzene.

EXAMPLE 13

Preparation of the diethylaminoethanol salt of nopic acid

This compound is prepared as described in Example 10 from nopic acid and diethylaminoethanol. This compound melts at 66–67° C. (benzene).

EXAMPLE 14

Preparation of the diisopropylaminoethanol salt of nopic acid

This compound is prepared as described in Example 10 from nopic acid and diisopropylaminoethanol. The compound melts at 72–73° C. after recrystallization from ethanol.

EXAMPLE 15

Preparation of the di-n-butylaminoethanol salt of nopic acid

This compound is prepared as described in Example 10 from nopic acid and di-n-butylaminoethanol. The white glasey compound cannot be recrystallized.

EXAMPLE 16

Preparation of the dimethylaminopropanol salt of nopic acid

This compound is prepared as described in Example 10 from nopic acid and dimethylaminopropanol. The pasty white product obtained by this process cannot be recrystallized.

EXAMPLE 17

Tablets of nopic acid derivative

		Mg.
50	Nopic acid derivative	100
60	Starch	100
	Talc	50
	Magnesium stearate	5

EXAMPLE 18

Vial for intramuscular injection

Nopic acid derivative—100 mg.
Buffering phosphate to pH—7.5
Apyrogenic water q.s. ad.—1 ml.

70

EXAMPLE 19

Suppositories

Nopic acid derivative—100 mg.
Cocoa butter q.s. ad.—1 suppository

EXAMPLE 20

Ointment

G.

Nopinic acid derivative	10
Ointment base (sodium lauryl sulfate, cetyl alcohol, petrolatum)	90

In Examples 17, 18, 19 and 20, the nopinic acid derivative is preferably the dimethylaminoethanol salt of nopinic acid or the hydrochloric of dimethylaminoethyl nopinate.

Many pharmacological tests have been made with the β -pinene, nopinic acid and derivatives thereof of Formulae I, II, II, IV and V, particularly with the dimethylaminoethanol salt of nopinic acid (S.N.D.).

Tests made on rats in order to determine the preventive anti-ulcer action of the compounds of Formulae I, II, III, IV or V, have shown that these compounds prevent the gastric ulcer caused by intermittent electrization of rats.

Extensive tests have also shown that said compounds have a cicatrizing effect on ulcers, such as hemorrhagic gastric ulcers and skin ulcers.

It has also been found that these compounds possess a strong antispasmodic and anticholinergic activity which is very useful in the therapy of the prevention and control of ulcers.

Other tests have also shown that the compounds reduce the gastric secretion and diminish the acidity of the gastric juice, said effects being favourable for the ulcer therapy.

All the esters and salts of nopinic acid of the Formulae IV and V are especially active, the compounds wherein R and R' represent identical methyl, ethyl, or propyl groups being the most active compounds. The best compound seems to be the dimethyl-aminoethanol salt of nopinic acid (called S.N.D.).

Clinical tests have also been made and have shown that SND has a very strong and consistent antalgic activity

on the gastro-duodenal ulcer, when the patients receive 300 to 400 mg. of SND per day (6 $\times$ 50 or 8 $\times$ 50 mg.). In several cases, a curative effect on the ulcer itself has been found.

What I claim is:

1. Compound corresponding to the general formula:

15 in which $n=1$ to 3 inclusive, whereas R and R' which may be identical or different, represent hydrogen or a lower alkyl radical.

2. Aminoethanol salt of nopinic acid.
3. Dimethylaminoethanol salt of nopinic acid.
4. Diethylaminoethanol salt of nopinic acid.
5. Monomethylaminoethanol salt of nopinic acid.
6. Diisopropylaminoethanol salt of nopinic acid.
7. Di-n-butylaminoethanol salt of nopinic acid.
8. Dimethylaminopropanol salt of nopinic acid.
